3 Sheets-Sheet 3

UNITED STATES PATENT OFFICE.

JOHN HART WILSON, OF BURKBURNETT, TEXAS.

WINCH.

Application filed November 3, 1924. Serial No. 747,655.

The present invention relates to winches, and more particularly to self-propelled winches used in oil field operations in raising from and lowering into oil wells tools, tubing, rods and other implements, although it may be also used for general hoisting and similar operations.

It is an object of this invention, generally stated, to provide an improvement on the type of winch disclosed in my prior Patent No. 1,499,045 and in the pending application filed by me on May 25, 1924, Serial No. 716,480.

More particularly, it is an object of this invention to provide in a winch construction similar to that described in the above patent a novel form of reversing mechanism whereby the drum may be positively reversed in order to accelerate lowering operations.

Another object of the invention consists in the provision of an attachment to be used on the drum for driving an auxiliary hoisting mechanism.

A still further object of the invention consists in the provision of an improved bearing member for the winch drum having provision thereon for retaining one end of a booming-down chain.

It is to be understood that in the accompanying drawings, there is disclosed one embodiment of the invention showing by way of example the preferred embodiment thereof, but that the design and arrangement of the component parts and elements may be greatly modified without departing from the spirit and scope of the invention.

In said drawings:

Figure 1 is a plan view of the improved winch mechanism attached to a Fordson tractor;

Figure 2 is a right side elevation thereof showing the right front and rear wheels removed;

Figure 3 is a longitudinal vertical section on line 3-3 of Figure 1;

Figure 4 is a transverse vertical section on broken lines 4-4 of Figure 3;

Figure 5 is a side elevation partly in vertical section of the detachable drum sprocket;

Figure 6 is a vertical section on broken line 6-6 of Figure 5;

Figure 7 is a section on line 7-7 of Figure 5; and

Figure 8 is a transverse vertical section 55 through the drum sprocket bearing taken on line 8-8 of Figure 1.

The tractor illustrated in the drawings is of the well known Fordson type, and the advantages of adapting this tractor for the purposes intended, from the standpoint of economy and simplicity of construction, will be apparent to those skilled in the art. However, the invention is limited to no particular form of tractor, and while in the embodiment herein disclosed, it is particularly adapted to a wheeled tractor, many of its features may be incorporated if desired in a tractor of the track laying type.

The crank case of the tractor is indicated 70 at 10, its engine block at 11, fuel oil tank at 12, radiator at 13, rear axle housing at 14, rear wheels at 15 and front wheels at 16. At 17 is shown the steering wheel, and at 18 the driver's seat. A number of the other features of the tractor which do not contribute 75 to the operation of the present invention have been omitted for the sake of clearness.

The winch drum is indicated at D, and the axle upon which this drum is non-rotatably secured extends transversely of the tractor and its ends are journaled in the babbitt lined bearings 19. As best shown in Figure 8, each bearing comprises a substantially cylindrical portion 20 having a 80 flattened surface 21 on the bottom thereof adapted to rest upon horizontally extending side frame members 22, and has the depending flange 23 having a transverse 85 strengthening web 24 connecting it to the lower outer section of the cylindrical portion 20. This flange 23 is adapted to be bolted to the web of the channel member 22 forming the horizontal side frame. For 90 convenience in babbetting the bearing, the end is closed as shown at 25 and provided with the central threaded opening 26 through which may be passed a threaded rod 95 having a conical point adapted to seat within the drilled center of the end of the shaft and thus support it centrally of the bearing, and when it is in this position babbet may be poured in to form the wearing 100 surfaces. Upon the upper surface of the

bearing member is cast the integral lug 27 slightly outward of the flange 28 and intended to retain in position a chain such as 28, which passes over the top of the bearing and beneath a timber or sill as 29 for the purpose of booming down the forward end of the tractor as is well known in the art. By providing the lugs on the bearing members and passing the chains over these members, the strain is transmitted directly to the shaft of the drum and not upon the side frame members and the fastening means holding the bearing to these members.

The side frame members 22 are, in the particular embodiment illustrated, formed of rolled steel channels with their flat faces outward. They project for a considerable distance in advance of the tractor, and the forward portions of these members are horizontally disposed, while the rearward portions are inclined downwardly, as best shown in Figure 2. They are provided at the lower rear ends with inwardly offset portions bifurcated as at 30 in order to rest on prepared seats on the rear axle housing. These ends are fastened to the rear axle by means of U-shaped bolts 31, surrounding the same, as shown in Figure 2. At their mid-points, the side frame members are supported by the inclined upright braces 32, the lower ends of which are bolted to the crank case flange by bolts 33, and the upper ends to the webs of the side frame members by bolts 34.

Laterally extending tying-in members 35 secure the top flanges of the side frame members to the head of the cylinder block to prevent lateral spreading of these members. In addition, the side frame members are connected together by a transversely extending channel member 36 in advance of the radiator 13. A V-shaped brace 37, best shown in Figures 1 and 2, which has its upper ends spread and secured to the bottom flange of the cross channel 36, extends downwardly and rearwardly and has its lower end connected to the crank case of the tractor by means of a longitudinal pin 38 which passes through the junction point of the two arms of the brace 37 and through the flanges 39 normally provided on the crank case of the tractor for the support of the usual front axle. The brace 37 is supplemented by a vertically extending brace 40 comprising angle irons 40 having their upper ends secured to the cross channel 36 and their lower ends supported from the front axle 41 which is moved forward for this purpose. These braces 37 and 40 support the forwardly extending portions of the side frame members 22 and transmit the weight of the drum and its associated mechanism to the frame and wheels of the tractor. The axle 41 is as usual mounted upon a longitudinal pivot 42 carried by the bi-

furcated arms 43 supported by the brace 40 and the longitudinal members 44 which connect it to the crank case at the flanges 39, previously described, and at the point 45 to which the radius rods are normally attached, means such as 46 being provided on these members 44 to anchor the rearward end of the radius rods. It will thus be seen that a simple and light frame mechanism is provided for supporting the winding drum, yet which frame is braced securely against all possible strains which may be imposed upon it. This frame, in addition to supporting the winding drum, supports the brake mechanism, the counter shaft, and other members of the control mechanism, as will be hereinafter more fully brought out.

Referring now more particularly to the winding drum itself, it will be seen that this drum comprises a cylindrical barrel portion 47 having the radial end flanges 48 provided with means for mounting the drum upon the previously mentioned shaft, and having also at their outer periphery the cylindrical brake drum portions 49 provided with the outer edge flanges 50 to prevent the brake bands 51 and 52 from slipping laterally off of the drums. The left hand brake band constitutes the emergency brake, and the right hand one the foot brake. To the outside of the left hand flange of the brake drum is secured a drive sprocket 53 by any suitable means, whereas the right hand end is provided inwardly of the brake drum with what is commonly known as a step-up drum 54 of larger diameter than the central drum portion 47 for rapidly taking in cable.

Extending transversely between the side frame members 22 and beneath the radiator reserve tank, is the counter shaft 55 having its ends rotatably mounted in bearings 56 bolted to the side frame members. Free to rotate on this shaft is a sleeve 57 having rigidly connected therewith the sprocket 58 connected by chain 59 with the sprocket 53 on the end of the winding drum, the inner face of this annular sleeve constituting a clutch face. A second sleeve 60 is splined to the shaft 55, and the outer face of this sleeve constitutes a corresponding clutch face adapted to cooperate with the face of sleeve 57. Due to its splined connection, sleeve 60 rotates with the counter shaft at all times, and may be moved longitudinally thereof by means of a bell crank lever 61 having a bifurcated end 62 the arms of which fit in a circumferential groove 63 in the sleeve 60. This lever is pivoted at 64 to a bracket on the tying-in member 35, and the transversely extending arm 65 thereof can be operated by means of a clutch shift lever 66, pivoted conveniently near the driver's seat to the left hand frame member 22, through the link 67. Movement of the

sleeve 60 into engagement with the sleeve 57 causes operative connection of the shaft 55 on the winding drum through the chain 59, and rotation of the counter shaft may therefore be communicated to the drum at the will of the operator by the simple movement of the hand lever 66.

Upon shaft 55 at the right hand end thereof and just inside of the bearing member 56, there is keyed or otherwise suitably secured, a large sprocket 68 which is connected by means of a chain 69 with a small sprocket 70 on the power take-off shaft 71 of the tractor. Power is therefore communicated through the two chains 69 and 59, counter shaft 55 and the clutch mechanism to the drum, and because of the construction of the clutch mechanism, the operator may quickly and conveniently connect the power shaft 71 to the drum at any time. At times, it may be desirable to take power from the counter shaft 55, since this runs at a slower speed than the power take-off of the tractor, and for this purpose the shaft 55 is extended on the right hand end beyond the bearing and provided with a catch 72 or any other suitable means.

It is often desirable to be able to rotate the drum D in a reverse direction for the purpose of rapidly paying out cable, or where it becomes desirable to drive an auxiliary hoisting apparatus or bull wheel, and for this purpose there is provided friction drive means for rotating the drum in a reverse direction than that in which it is normally driven by means of the chain 59. Referring to Figures 3 and 4, it will be noted that this friction drive member comprises a friction disc 73, which may be of any suitable composition, such as compressed paper clamped between two reinforcing discs 74, all mounted upon a bearing sleeve 75 which is preferably formed of bronze. The inner end of this bearing sleeve, as shown in Figure 4, has rigidly attached thereto a small sprocket 76 which is adapted to be driven by the chain 77 from the sprocket 78 mounted upon the counter shaft 55 closely adjacent the large sprocket 68 thereon, by means of which it is driven from the power takeoff.

This friction member or disc, it will be observed, is driven at all times from the counter shaft, but is adapted to be engaged with the surface of the brake drum on the right hand end of the hoisting drum only at such times as the clutch members 57 and 60 are disengaged. For the purpose of engaging and disengaging the friction disc with the surface of the brake drum, as shown in Figure 3, the bearing sleeve 75 is journaled upon the shaft 79 which has the eccentrically disposed, reduced ends 80 journaled for rotation in the two vertically disposed portions of the bracket 81, which will be later de-

scribed. The outer reduced end 80 is extended and provided with a vertically extending actuating arm 82 which is connected by means of a link 83 to the hand lever 84 pivoted at 85 upon the outside of the right hand frame member 22 near the driver's seat.

A spring 86 serves to retract the connecting rod 83 and so position the eccentric shaft 79 that the face of the friction disc 73 is withdrawn from contact with the face of the brake drum. When the operator desires to reverse the direction of motion of the winding drum, he first disconnects, by means of the lever 66, the two parts 57 and 60 of the forward drive clutch, and then pulls rearwardly on the lever 84 and thus rotates the eccentric shaft 79 in a counter-clockwise direction, as viewed in Figure 3, and thus causes the face of the friction disc 73 to engage the face of the brake drum 49 and rotate the winding drum in a direction opposite to that normally transmitted to it by means of the chain 59, since the friction disc 73 is driven in the same direction as the counter shaft and transmits motion in an opposite direction to the brake drum. The effort to maintain contact between the two members of the friction drive is supplied by the operator so that immediately upon release of the lever 84, the spring 86 will retract the lever 82 and disconnect the friction disc and the brake drum.

The lower end of each brake band 51 and 52 is connected by suitable rivets to a rod 87 disposed tangentially to the braking surface 100 and having its outer end threaded and extending through a suitable aperture in a bracket 88 riveted to the cross channel member 36. Suitable nuts 89 on opposite sides of brackets 88 permit rods 87 to be longitudinally adjusted so that the tightness of the brake bands may be quickly adjusted. The upper ends of the brake bands are looped, and that of the left hand one 52 extends around a pin passing through apertures in the parallel arms 90 of the short brake lever 91, which is loosely mounted upon the brake shaft 92 which extends transversely of the machine and has its ends rotatably mounted in bearings 93 and 94 respectively. Bearing 93 is mounted upon the left hand frame member, while bearing 94 forms a part of the member which supports the friction drive. Collar 95 is secured by a set screw on the shaft 92 to prevent longitudinal movement of the member 91, which is provided with a lever arm 96, the end of which engages the inner face of the bearing 93, and together with the collar 95 prevents movement of the brake arm 91 longitudinally of the shaft. To the upper end of the lever 96 is connected the link 97, the rearward end of which is connected to the emergency brake lever 98 conveniently pivoted to the side frame near the driver's seat and

having a suitable latch and quadrant for retaining it in any desired position.

- The right hand brake 51 has its upper end looped and extended around the pin 99 5 pivoted between the spaced arms 100 of the brake lever 101 which is securely keyed or otherwise suitably fastened to the short brake shaft 102 pivoted in the upwardly extending bearing members 103 integral with 10 the members which form the bearings for the friction drive disc. The shaft 102 is connected for rotation with the brake shaft 92 by means of the lever arms 104 and 105 rigidly secured to the two shafts respectively, 15 normally parallel and connected together at their ends by the link 105' so that any partial rotation given to shaft 92 will be transmitted to shaft 102 and thence to the pin 99 to effect operation of the brake. Shaft 92 20 is rotated by means of the arm 106 securely fastened thereto outside of the bearing member 93. To the upper end of this arm 106 is pivoted the forward end of a link 107, the rear end of which is in turn pivoted to the 25 upper end of a rocker arm 108 rotatably mounted upon a shaft 109 supported in bearings 110 secured to the side frame member. Rigidly connected by means of the short shaft 109 with rocker arm 108, but at a 30 slight angle thereto, is a second rocker arm 111, and to the upper end of this arm is pivotally connected a link 112, the lower end of which is in turn pivotally connected to the downwardly extending flange 113 of 35 a foot pedal 114 which is mounted to rock on a short shaft 115 suitably supported between the rear axle housing and one of the side members of the frame. A spring 116 having one end connected to the drum shaft 40 bearing and the other end connected to lever 106 tends to draw the lever forwardly and the foot pedal upwardly from its limiting stop, not illustrated, to release the brake. Depression of the foot brake pedal causes 45 tensioning of the spring and applies the foot brake, and upon release of the pedal by the operator, the spring will act to draw lever 106 forwardly and hence to cause release of the foot brake.
- 50 It will be noted that the construction of the left or hand brake is exactly similar to that disclosed in the above mentioned application, but it has been found necessary to change the construction of the right hand or 55 foot brake to provide means for the accommodation of the friction drive mechanism which operates at the point on the brake drum occupied by the brake band.
- The member which combines the bearings 60 for the friction drive disc and the brake shaft 102 comprises a unitary casting 81 having the pair of parallel sides 117 and 118 connected together near their bottoms by T-sectioned bar 119, and at their rear side, in 65 the same horizontal plane as the friction

disc bearings, by the T-shaped member 120 and near the top by the bar 121. The side members 117 and 118 are provided with the feet 122 and 122' respectively, the latter of which has the downwardly projecting flange 70 123 which is adapted to be secured to the outer face of the side frame member, while the foot 122' rests upon and may be bolted to the upper flange of this side member. An additional right-angled bracket member 124 75 has one arm thereof bolted to the inner face of the transverse channel 36 and is provided with the reinforcing web 125 between the vertical and longitudinal arms. The upper face 80 126 of this reverse bracket member is adapted to support the foot 122 which is bolted thereto in any suitable manner. The edge of this foot 122 which is in front of the channel 36 is provided with a vertical hole through which passes the bolt 127 provided with the 85 nut at the upper end thereof and the ring shaped lower end through which the bolt 128 which fastens the bracket 124 to the channel member 36 passes, thus serving to hold down the inner forward corner of this bearing 90 member. The bracket 124 has formed integral therewith the bearing member 94 for the brake rod 92. The two sides 117 and 118 of the main bearing member are provided with suitable bosses for the reception of the 95 shafts 80 and 102, with reinforcing webs connecting the bosses and feet for strengthening purposes. All of the holes whereby this composite bearing member is connected to the frame are elongated in the direction 100 of the length of the machine in order that any wear on the friction disc may be taken up by sliding its bearing member toward the brake drum. In order to more readily effect this sliding, a bracket 129 is secured to the upper face of the right hand frame member and provided with the bolt 130 threaded into the vertical arm thereof, which bolt bears against a projection on the side 118 of the bearing member to press it forwardly, a lock nut being provided to retain the bolt in its desired position. There is sufficient slack provided in the chain 77 to allow this adjustment and also to allow for the rotation of the eccentric shaft of the 110 friction disc to bring it into engagement with the brake drum.

As previously mentioned, it is sometimes found desirable to drive an additional drum separate from the winding drum on the 120 winch, since this may give an added gear reduction and considerably increase the pulling power of the winch. For this purpose a sprocket may be mounted on the winding drum of the winch and an additional sprocket 125 on the drum or bull wheel of the derrick. Since this bull wheel is usually of rather crude construction, the reverse previously described is necessary to drive it when it is desired to unwind cable therefrom. In Fig. 129

ures 1, 5, 6 and 7 is disclosed an auxiliary split sprocket which may be conveniently mounted upon the winding drum when it is desired to use the construction just explained.

The auxiliary sprocket 131 is provided with the elongated hub 132 having the circumferential end flange 133, and both the hub and sprocket are divided in two parts 10 along a diametrical plane, as shown at 134 in Figure 5, in order that they may be readily fitted over the barrel 47 of the winding drum, the bore 135 through the hub being of such a diameter as to closely fit upon this 15 drum. The flange 133 is widened at four points, such as at 136 and longitudinally drilled for the reception of bolts, by means of which the flange can be bolted to the inner left hand end of the brake drum structure to 20 retain the sprocket in position and prevent it from rotating in respect to the drum. The two halves of the inner or sprocket end of the construction are adapted to be held together by the interlocking mechanism disclosed 25 in Figures 5, 6 and 7. Two such interlocking constructions are provided, one at each radial joint 134, but one of which is illustrated for the sake of example since they are identical. One portion of the 30 sprocket is provided with a projecting member 137 adapted to fit into a slot 138 in the corresponding member, so that the two halves may be brought together about the drum 47 and allow the projection 137 to 35 enter the slot 138, after which a tapered pin 139 may be passed longitudinally through corresponding holes in the sides of the part forming the slot and in the projection 137, this pin being retained in position by cotter pin 140, as best shown in Figure 7. It is 40 believed that this construction is clearly illustrated in the drawings and further description is not necessary. However, it may be stated that the two parts of the sprocket 45 may be readily separated by withdrawing the two tapered pins 139 and removing the four bolts which hold the flange 132 against the brake drum. The hub portion is elongated, as shown, in order to space the sprocket 50 a material distance inward from the brake drum flange to provide a place for carrying spare cable or line when such a line is used on the winch drum as for pulling rods, etc. The surplus line which is not used 55 in the operation is always in the way, and it has been usual to provide on the drum a divider, but in this case the function is 60 equally well performed by the sprocket. The spare line, when it is desired to use a 65 part of it, may be simply crossed over between the teeth of the sprocket which prevents it from slipping around onto the main drum.

The tractor above described may be driven 70 rapidly from one oil well or scene of op-

eration to another, and is positioned for operation quickly by merely moving it up to the sill of the oil derrick, as shown in Figure 2. The booming-down chains may be quickly secured beneath this sill and over 75 the drum bearings and the cable passed from an elevated block or pulley to the winch drum. The three controls of the winch mechanism proper may be easily operated by an inexperienced person. By engaging the clutch, the cable may be wound on the drum, and when the clutch is released, the drum under ordinary conditions will automatically unwind due to the weight 80 on the end of the cable. The speed of lowering the tube or rod will depend upon the retarding action which the operator exerts on the drum by means of the brake. By means of the emergency or hand brake, the drum may be locked at any time. In 85 such cases where the weight upon the cable is not sufficient or where the friction of an additional winding drum will not cause unwinding of the drum when the clutch is released, the operator by pulling upon the 90 lever 84 can effect engagement between the friction drive disc and the right hand brake drum and cause the drum to be driven positively in a reverse direction, which motion 95 may be stopped at any time by merely releasing the lever 84 which is then pulled forward by the spring and applying the brake if necessary. The use of the chain and sprocket connection between the power 100 take-off shaft and the drum gives a flexibility and smoothness of operation not heretofore realized in self-propelled winches, and the friction connection used in the reversing operation combines not only a drive 105 but also a clutch. By the use of the auxiliary sprocket on the winding drum, an additional drum on a stationary derrick may be operated, if desired, by passing a chain between the two, and additional power step-up may be obtained.

As previously pointed out, the principles of the invention may be carried out in different ways, and the self-propelled winch, above described and illustrated in the accompanying drawings, is given by way of example only. The design and arrangement of the component elements of the invention may be varied and modified considerably without departing from the spirit and scope 115 of the invention.

Having thus described my invention what I claim as new and desire to be secured by Letters Patent is:

1. A self-propelled winch mechanism of the class described, including in combination, a winding drum journaled for rotation about a fixed axis, a brake drum rigid therewith, a brake band surrounding the major portion of said brake drum and adapted to cooperate therewith to retard or stop its 125

- movement, a source of power, a counter-shaft driven thereby, means including clutch mechanism to drive said drum in the same direction as said countershaft, a friction disc constantly driven from said counter-shaft, and means enabling said disc to be brought into engagement with said brake drum at a portion of its periphery free from said brake band, to drive said drum in a reverse direction.
2. A self-propelled winch mechanism of the class described, including in combination, a rotatably mounted winding drum, a brake drum rigid therewith, a brake band surrounding the major portion of said brake drum and adapted to cooperate therewith to retard or stop its movement, a source of power, a counter-shaft driven thereby, means including clutch mechanism to drive said drum in the same direction as said counter-shaft, a friction disc constantly driven from said counter-shaft, an eccentrically mounted shaft for said disc, and means to rotate said shaft to engage said disc with said brake drum, where it is free from said brake band to drive it in a reverse direction.
3. A self-propelled winch, including in combination, a rotatably mounted winding drum, a brake drum fastened thereto, a brake band adapted to cooperate with said brake drum, a source of power, a counter-shaft adapted to be constantly driven thereby, a sprocket thereon, a sprocket attached to said winding drum, a chain connecting said sprockets, means to free said first sprocket from said counter-shaft, a friction disc adjacent the periphery of said brake drum, a sprocket attached thereto, a second sprocket on said counter-shaft, a chain connecting said sprockets, and means to, at will, engage said friction disc with said brake drum.
4. A self-propelled winch, including in combination, a rotatably mounted winding drum, a brake drum fastened thereto, a brake band adapted to cooperate with said brake drum, a source of power, a counter-shaft adapted to be constantly driven thereby, a sprocket thereon, a sprocket attached to said winding drum, a chain connecting said sprockets, means to free said first sprocket from said counter-shaft, a friction disc adjacent the periphery of said brake drum, a sprocket attached thereto, a second sprocket on said counter-shaft, a chain connecting said sprockets, and shiftable means supporting said friction disc for rotation thereon, whereby said disc may engage the periphery of said brake drum to rotate said winding drum, said chain having sufficient slack to allow movement of said disc.
5. A self-propelled winch, including in combination, a tractor, a source of power therefore, side frame members carried by said tractor, fixed bearings in said frame members, a winding drum rotatably supported in the said bearings, a brake drum secured to one end of said winding drum, a counter-shaft driven from said source of power, disconnectible means for driving said winding drum from said counter-shaft, a friction disc rotatably supported in bearings on one of said side frame members adjacent to said brake drum, means to continuously drive said disc from said counter-shaft, and means to at will engage said disc to drive said drum.
6. A self-propelled winch, including in combination, a tractor, a source of power therefor, side frame members carried by said tractor, a winding drum rotatably supported between said frame members, a brake drum secured to one end of said winding drum, a brake band therefore having one end secured to one of said frame members, a counter-shaft driven from said source of power, disconnectible means for driving said winding drum from said counter-shaft, a friction disc rotatably supported in bearings on one of said side frame members adjacent to said brake drum, means to continuously drive said disc from said counter-shaft, and means to at will engage said disc to drive said drum, the opposite end of said brake band having a connection with the bearings for said disc.
7. A self-propelled winch, including in combination, a tractor, a source of power therefor, side frame members carried by said tractor, a winding drum rotatably supported between said frame members, a brake drum secured to one end of said winding drum, a brake band therefore having one end secured to one of said frame members, a counter-shaft driven from said source of power, disconnectible means for driving said winding drum from said counter-shaft, a friction disc rotatably supported in bearings on one of said side frame members adjacent to said brake drum, means to continuously drive said disc from said counter-shaft, and means to at will engage said disc to drive said drum, the opposite end of said brake band having a link connection with the bearings for said disc, and means to tension said band about the drum.
8. A self-propelled winch, including in combination, a tractor, a source of power therefor, side frame members carried by said tractor, a winding drum rotatably supported between said side frame members, a brake drum at either end of said winding drum, a brake band for each drum, each band having one end secured to a frame member, disconnectible means for driving said winding drum from said source of power, a friction disc driven from said source of power, bearing brackets mounted on one of said frame members and support-

ing said disc in proximity to the periphery of one of said brake drums, means to engage said disc with said drum to drive it in a reverse direction, a brake shaft journaled in said brackets, a brake lever on said shaft connected to one of said brake bands, a second brake shaft journaled between one of said brackets and the opposite frame member, and means to rotate one brake shaft 10 from the other.

9. A self-propelled winch, including in combination, a tractor, a source of power therefor, side frame members carried by said tractor, a winding drum rotatably supported 15 between said side frame members, a brake drum at either end of said winding drum, a brake band for each drum, each band having one end secured to a frame member, disconnectible means for driving said winding 20 drum from said source of power, a friction

disc driven from said source of power, bearing brackets mounted on one of said frame members and supporting said disc in proximity to the periphery of one of said brake drums, means to engage said disc with said 25 drum to drive it in a reverse direction, a brake shaft journaled in said brackets, a brake lever on said shaft connected to one of said brake bands, a second brake shaft journaled between one of said brackets and the 30 opposite frame member, means to rotate one brake shaft from the other, a sleeve on said second shaft, a lever thereon connected to said second brake band, and means to operate either said second shaft or said sleeve 35 to apply braking effort to said drum.

In testimony whereof I hereunto affix my signature.

JOHN HART WILSON.
